(57) **CLAIM**

The ornamental design for the electrical connector, as shown and described.

DESCRIPTION

FIG. 1 is a perspective view of an electrical connector showing our new design, showing the first and second portions of the electrical connector coupled together;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a left side end view thereof;

FIG. 7 is a right side end view thereof;

FIG. 8 is a perspective view of the first portion of the electrical connector of FIG. 1, shown separately for clarity of detail;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a left side end view thereof;

FIG. 14 is a right side view thereof;

FIG. 15 is a perspective view of the second portion of the electrical connector of FIG. 1, shown separately for clarity of detail;

FIG. 16 is a top view thereof;

FIG. 17 is a front elevational view thereof;

FIG. 18 is a bottom view thereof;

FIG. 19 is a rear elevational view thereof;

FIG. 20 is a left end view thereof;

FIG. 21 is a right side view thereof;

FIG. 22 is a front elevational view of the electrical connector of FIG. 1 showing a typical usage condition with protective caps and an electrical core in phantom lines;

FIG. 23 is a perspective view of the first portion of the electrical connector of FIG. 8 showing a typical usage condition with a protective cap in phantom lines coupled to the connector; and,

FIG. 24 is a perspective view of the second portion of the electrical connector of FIG. 15 showing a typical usage condition with a protective cap in phantom lines coupled to the connector.

The broken line portions of the figure drawings are included to show unclaimed subject matter and environmental usage detail only and form no part of the claimed design.

1 Claim, 6 Drawing Sheets
